William A. Redlin, Encino, Calif., assignor to Redlin Productions, Inc., Los Angeles, Calif.,
a corporation of California

Application April 7, 1951, Serial No. 14,746

Term of patent 14 years

(Cl. D34—2)

To all whom it may concern:

Be it known that I, William A. Redlin, a citizen of the United States, residing in Encino, in the county of Los Angeles and State of California, have invented a new, original, and ornamental Design for a Mask for Disguise or the like, of which the following is a specification, reference being had to the accompanying drawing, forming part thereof.

Fig. 1 is a front view of a mask for disguise or the like, showing my new design.

Fig. 2 is a side view thereof.

Fig. 3 is a vertical sectional view.

I claim:

The ornamental design for a mask for disguise or the like, substantially as shown.

WILLIAM A. REDLIN.
